Patented June 26, 1923.

UNITED STATES PATENT OFFICE.

WARREN B. REED, OF MORGAN CITY, LOUISIANA.

PROCESS OF SETTING CASING AND CEMENTING THE SAME.

Application filed May 8, 1922. Serial No. 559,243.

To all whom it may concern:

Be it known that I, WARREN B. REED, a citizen of the United States, residing at Morgan City, parish of St. Mary, Louisiana, have invented a certain new and useful Improvement in Processes of Setting Casing and Cementing the Same, of which the following is a full, clear, and exact description, such as will enable others skilled in the art 10 to which it appertains to make and use the same.

My invention relates to a process of setting and cementing the casing in the operation of drilling deep wells.

15 In the drilling of wells for oil, gas, sulfur, etc., it is very often advisable to set the casing tightly in the hole before the pay stratum is opened up. This operation is especially desirable where high gas pressure exists in the stratum being drilled into. The process now in use is usually to fill the lower end of the hole with cement, set the lower end of the casing firmly on the bottom of the hole in the stratum above the pay and to allow 20 the cement to set. This is a difficult process to accomplish successfully, especially if any gas is rising, for the gas forces itself in bubbles upwardly into the cement while it is fresh and makes the cement porous and 25 prevents the proper setting of the same.

An object of my invention is to provide a process of cementing the casing so that the closure of the hole about the lower end of the casing will be complete and the gas be 30 prevented from mixing with the cement.

Another object is to simplify the operation of cementing and to reduce the amount of time and labor to a minimum.

Another object is to provide a process of cementing whereby the hole may be thereafter drilled further into the pay stratum with a minimum of difficulty and without danger of injuring the well.

These and other objects and advantages 45 will be apparent to one skilled in the art from the detailed description which follows.

Referring to the drawing herewith wherein like parts are referred to by like numerals of reference in all the views.

50 Figure 1 is a central longitudinal section thru a well with an apparatus therein whereby my process may be performed.

Figures 2 and 3 show similar views with the parts adjusted into different positions; 55 and

Figure 4 shows the device used in a hole which has been probed ahead and in which a back pressure valve is employed.

In the carrying out of my process, I contemplate setting the casing firmly on the bottom of the hole, expanding a packer on the casing immediately above the bottom and then filling the space outside the casing above the packer with cement for a suitable distance and allowing the cement to set. 60 To carry out this process I employ an apparatus similar in construction to that shown in my copending application No. 548068, filed March 20th, 1922.

The casing 1 to be set has, near the lower end thereof, an enlarged nipple 2 connected to said casing by a collar 3. The nipple 2 telescopes over a length of pipe or liner 4 which projects upwardly into said nipple a short distance as shown in Fig. 1. The nipple is internally threaded at its lower end for attachment to said pipe 4 which is enlarged slightly and threaded at 5 for detachable connection with the nipple.

Said pipe 4 has at its lower end a collar or 70 shoe 6. This shoe is slotted interiorly at 7 to receive a pointed blade 8, the purpose of which is to set firmly in the bottom of the hole and prevent the free rotation of the pipe.

Intermediate the ends of pipe 4 is secured a canvas packer 9. At its lower end said packer is wired to the pipe at 10. The upper end of the packer is attached to collar 11, slid on the outer surface of said pipe. 90 Said collar is reduced somewhat in thickness below the upper end to receive the said packer. The collar 11 is detachably secured to said pipe 4 by means of pins 12 which may be made of any soft or brittle 95 metal easily sheared or broken when desired.

Inside the packer, adjacent the upper end thereof, the pipe 4 is perforated at 13 for a short distance and it will be noted that, 100 with the parts as shown in Fig. 1, these perforations will be covered by the collar 11.

In carrying out my process, the casing, packer and shoe are lowered to the bottom of the well and are then raised slightly off the bottom, as shown in Fig. 1, and flushing fluid is pumped down through the casing to wash out the well and clear it of obstructions. The casing is then forced down on to the bottom so as to bury the blade 8 110

in the material and close the bottom of the casing. The blade will serve to prevent the rotation of pipe 4 and the packer.

The casing and nipple 2 will then be rotated in a right hand direction thus screwing the nipple down on the pipe 4 and releasing the connection at 5. When thus released the nipple and casing will be lowered on to the collar 11 thus shearing off pins 10 12 and moving collar 11 downwardly to expand the packer as shown in Fig. 2. A tamping action of the casing will thoroughly expand the packer so as to close the space outside the pipe 4.

15 The casing will then be raised to expose the openings 13 thus opened by the movement of the collar 11. Cement will then be pumped down into the casing and forced outwardly through the foraminations 13

20 into the space above the packer. When a suitable quantity of cement has thus been forced into this space, the casing will be lowered to close the openings 13 and the casing rotated to settle the cement in place

25 around the same. A smaller pipe or drill stem may then be lowered into the bottom of the well and flushing fluid be pumped down therethrough to clear the interior of the casing of cement remaining within the

30 casing. The drill stem may then be withdrawn and the cement allowed to set.

If there has been a probe hole, such as shown at 14 in Fig. 4, drilled to test the formation, it may be necessary to use a back pressure valve of ordinary construction 15. This will prevent the gas from escaping up through the casing.

When the cement is set a milling tool may be used to drill out the blade 8 and back 40 pressure valve 15 and the hole may thereafter be extended on into the pay stratum.

The advantages of my improved process lie in the fact that a packer is used to close the bottom of the hole before the cement is introduced. No gas can then mix with the cement while it is setting or hardening. The pay stratum is shut off not only by a proper cementing job but the packer also materially aids in closing the 45 well outside the casing. The casing may

be set quickly and accurately and the cement distributed about the casing so as to assure a proper closure.

Having thus described my invention, what I claim is new and desire to protect 55 by Letters Patent is:

1. In the operation of setting and cementing casing in wells, the improvement consisting of setting the casing firmly on the bottom, closing the space outside the casing 60 adjacent the bottom by a packing means, forcing cement downwardly through the casing into the space above said packing means, washing out the interior of the casing and allowing the cement to set. 65

2. In the operation of setting and cementing casing in wells, the improvement consisting of introducing the casing, washing out the well, setting the casing firmly on the bottom, setting a packer above the bottom, forcing cement downwardly through the casing into the space above the packer, and allowing the cement to set. 70

3. In the operation of setting and cementing casing in wells, the improvement 75 consisting of introducing the casing into the well, setting said casing firmly on the bottom, packing the space outside the casing adjacent the bottom, introducing a suitable quantity of cement into the space above 80 the packing and allowing the cement to set.

4. In the operation of setting and cementing casing in wells, the improvement consisting of lowering the casing to the bottom of the hole, setting a packer adjacent 85 the lower end and introducing cement into the space outside said casing above the packer.

5. In the operation of setting and cementing casing in wells, the improvement 90 consisting of lowering the casing to the bottom of the hole, washing the hole, setting a packer adjacent the lower end, introducing cement into the hole above the packer, washing out the interior of the casing and 95 allowing the cement to set.

In testimony whereof, I hereunto affix my signature, this the 26 day of April, 1922.

WARREN B. REED.
